UNITED STATES PATENT OFFICE

JAMES M. GREGORY, OF NEW YORK, N. Y.

AUTOMATIC SIGNAL SERVICE

Application filed February 6, 1929. Serial No. 337,743.

This invention relates to road signals and similar devices for displaying legends, signs and the like intermittently from each of its circular sides.

Devices of a similar nature are commonly used at railroad crossings, street intersections for directing traffic, and also for display purposes of various nature, depending for their operation upon an electric current, 10 spring actuated motors, etc. liable to failure at critical moments, and which require frequent inspection and adjustment.

Having these matters in view, it has been an object of the present invention to provide 15 an essentially simple signal device in which gravity alone is used as an actuating means and which requires attention only at infrequent intervals.

A further feature is in the provision of 20 means whereby the signals may be changed automatically and each displayed during like or unlike intervals of time selectively.

These and other advantageous features are accomplished by the novel construction and 25 combination of parts as hereinafter described and shown in the accompanying drawings, forming a material part of this disclosure and in which:—

Figure 1 is a front elevational view of a 30 complete signal apparatus embodying the invention.

Figure 2 is a side elevational view of the same, partially broken away to show interior elements.

Figure 3 is a side elevational view of the 35 operative mechanism.

Figure 4 is a front view of the same.

Figure 5 is a sectional view taken on line 5—5 of Figure 4.

Figure 6 is a perspective view of the driving segment and associated parts.

The device is shown as mounted on an upright tubular post 10 firmly set at its lower end in the ground and having at its upper end 45 a collar 11 engaged with a flat sided cylindrical casing 11.

Set in the sides of the casing are discs 13 containing openings 14 covered by transparent plates, as glass through which may 50 appear differently colored portions of cir-

cular plates 17 rigidly fixed at their axes on the opposite ends of an arbor 18 mounted to rotate in the spaced side plates 19—19' of a rectangular frame disposed within the casing.

The plates are firmly held in spaced relation near their corners by rods 20 and are provided with a plurality of bearings for spindles as will appear.

One of the spindles 21, in the upper portion of the plates, has fixed upon it a drum 22, having at one end a freely revoluble sprocket wheel 23 carrying on its outer face an escapement dog 24 engageable with a ratchet wheel 25 fixed to the spindle, as is also 60 a spur gear 26.

Attached at one end to the drum to be wound thereon, is a cord 27 passing about a guide pulley 28, freely revoluble on a spindle 29 supported by the plates 17, then down 70 through an opening in the lower peripheral edge of the casing 12, into the tubular post 10 and thence around a pulley 30 journaled on a spindle 31 fixed transversely in the upper end of a weight 32 freely movable up and 75 down within the post.

Thence the cord is brought up to pass over a similar guide pulley 28', down around another pulley 30', on the weight carried spindle, up around another guide pulley 28'' 80 and again to the weight at 30'', this circuit providing a very considerable length of cord between the weight 32 and drum 22 which is obviously actuated by it through gravity.

The cord is initially wound upon the drum 85 by a hand chain 33 trained over the sprocket wheel 23, guided by a pulley 34 and thence around a guide sprocket 35 in the post 10, the post being provided with a door 36 through which the chain is accessible for manipulation in winding the drum through the intermediary of the dog 24 and ratchet 25.

As the weight is lowered and the spindle 21 revolved, the spur gear 26 is turned with it, causing a pinion 37 in mesh with it to 95 rotate on its spindle 38, on which is secured a gear 39 meshing with a pinion 40 fixed on the arbor 18.

Also fixed on the arbor 18 is a cam 41 having opposed lifting arms 42—42', one of 100

which may be longer than the other, these arms being alternately engageable with the body portion of a segment 43, pivoted in the casing at 44, so that the segment will be raised at intervals and drop rapidly by gravity when the arms rotate past the body portion abutment 43'.

5 A lever 45, pivoted at the center of its length at 46, has a weighted end 45' and a notch 47 near its front end to engage the arm terminals when the segment 43 is raised, a portion of the segment normally resting on the end of the lever, causing it to tilt, raising the weight on releasing the arms, due to the action of the weight of the segment.

10 The peripheral edge of the segment 43 is provided with spur gear teeth 43'', the same engaging a pinion 48, fixed on the side of a ratchet wheel 49, freely mounted on a stud 50.

15 Alongside the wheel 49 is a spur gear 51 carrying a pivoted pawl 52 engaging the teeth of the ratchet wheel to impart motion to the gear during the time of descent of the segment, but remaining quiescent as it is raised.

20 Driven by the gear 51 is a gear train consisting of a pinion 53 fixed alongside a gear 54 on a stud 55 set in the frame plate 19, the gear driving a pinion 56 fast upon a shaft 57, this shaft carrying spring leaves 58 to which are attached weights 59, consisting a common form of centrifugal governor to limit the speed of the shaft and hence the rapidity of descent of the segment within 25 desirable bounds.

25 The opposite ends of the spring leaves 58 are attached to a collar 60 freely slidable on the governor shaft 57 and carry a disc 61 to make frictional contact with a plate 62 carried by a stud 63 adjustable in the opposite frame plate 19.

30 In operation, the door 36 is opened, the chain 33 actuated by hand to raise the weight, and thus energize the drum, the power of which is transmitted to the segment through 35 the cam intermittently and, as the rotatable disc is secured on the cam spindle, a different showing of the signals is attained alternately.

35 It is also to be noted that the entire mechanism is entirely enclosed in a weather proof casing; so as to be unaffected by wind, water, freezing or like occurrences, and that the action of the several parts is dependent upon gravity rather than springs or like uncertain 40 and unreliable features.

45 The device can be adjusted for speed by the element 63 and by making the arms of the cams of unequal length the showing of the signals may be varied in time period 50 proportionally.

55 From the foregoing it will be seen that a simple device for this purpose has been disclosed in the preferred form of its embodiment, but it is not desired to restrict the 60 details to the exact construction shown, it

being obvious that changes, not involving the exercise of the invention, may be made without conflicting with the scope of the appended claims.

Having thus described the invention, what is claimed as new and desired to secure by Letters Patent, is:—

70 1. A signal apparatus comprising a hollow post, a cylindrical casing mounted on said post at a transverse axis thereto, a frame fixed in said casing, plates having transparently covered openings set in the ends of said casing, parti-colored discs revoluble in said frame adjacent said plates, mechanism carried by said frame for intermittently imparting a semi-rotation to said discs, and a gravity impelled device for actuating said mechanism.

75 2. A signal apparatus comprising a hollow post, a cylindrical casing mounted on said post at a transverse axis thereto, a frame fixed in said casing, plates having transparently covered openings set in the ends of said casing, parti-colored discs revoluble in said frame adjacent said plates, a gravity actuated mechanism for intermittently producing semi-rotation of said discs, and means for controlling the speed of operation of said mechanism, all of said elements being contained within the casing.

80 3. A signal apparatus comprising a hollow post, a cylindrical casing mounted on said post at a transverse axis thereto, a frame fixed in said casing, plates having transparently covered openings set in the ends of said casing, parti-colored discs revoluble in said frame adjacent said plates, a gravity actuated mechanism for intermittently producing semi-rotation of said discs, and means for controlling the speed of operation of said mechanism, all of said elements being contained within the casing.

85 4. A signal apparatus comprising a hollow post, a cylindrical casing mounted on a transverse axis on said post, said cylinder having closed ends provided with transparently covered openings, a frame fixed in said casing, a pair of discs having differently colored portions revolubly mounted in said frame, a weight actuated gear train, a double ended cam driven by the gear train, a toothed segment operated thereby, a second gear train driven by said segment, a governor actuated by the last named train, and means combined with said cam to rotate said discs intermittently.

90 5. In a signal apparatus having opposed perforate faces and parti-colored discs revoluble adjacent the faces, an arbor on which the discs are fixed, weight actuated means for rotating said arbor, a two armed cam on said arbor, a toothed segment pivoted to be raised by each cam arm intermittently, a weight actuated lever engageable with the cam arms during the descent of said segment, said lever being disengaged from

said arm by contact with the segment when in its lowermost position, and means driven by the teeth of said segment to control the rate of operation of the segment.

6. In a signal apparatus having opposed perforate faces and parti-colored discs revoluble adjacent the faces, an arbor on which the discs are fixed, weight actuated means for rotating said arbor, a two armed cam on said arbor, a gravity actuated segment pivoted in operative relation to said cam to be raised and released thereby at intermittent intervals, a weight actuated lever having a notch to detain said cam from movement during the descent of said segment, and means to release said cam from the lever notch when said segment has reached the extremity of its downward movement.

In testimony whereof I affix my signature.

JAMES M. GREGORY.
